ROBERT E. PETERSON, OF NEW YORK, N. Y., ASSIGNOR, BY MESNE ASSIGNMENTS, TO
ELECTRIC STEAM GENERATORS, INC., OF NEW YORK, N. Y., A CORPORATION OF
DELAWARE

TOILET SEAT STERILIZER

Application filed June 13, 1931. Serial No. 544,183.

An object of the invention is to provide a sterilizer which will automatically sterilize a toilet seat after it has been used. The sterilizer is provided with means which will prevent injury to the user and which will make the sterilizer certain in its operation even when the normal movement of its exposed parts is interfered with.

The toilet seat is preferably made in two sections and there are two compartments in which the toilet seat sections are sterilized, the compartments each having a door. There are means for moving each section of the toilet seat yieldingly in and out of its compartments so that, if the movement of one section is interfered with, the other section will move normally and the section which is interfered with will quickly move to its normal position when the interference is removed. If the driving means were not stopped in certain cases when the movement of a toilet seat section is interfered with, the cycle of operation would be broken. Therefore, there are means to stop the driving means to prevent such an occurrence.

When the toilet seat sections are moved to positions spaced above the bowl, the driving means is stopped and any further downward movement of the seat sections will set means to again start the driving means, when the toilet seat sections again assume their position spaced above the bowl, means being provided to stop the driving means when the user has left the seat sections momentarily and has returned thereto.

The doors closing the sterilizing compartment are opened and are closed yieldingly, and when the movement of a door is interfered with, the other door will move normally and the door which has been interfered with will quickly assume its normal position when the interference is removed. Means are provided to lock the doors when they have been closed, and means are also provided to stop the cycle of operation and to prevent the commencement of the sterilization of the toilet seat sections in the compartments until the doors have been closed and locked.

Additional objects of the invention are to

provide means to introduce steam into the compartments for sterilizing the seat sections when the doors have been closed and locked. The seat sections have inclosed cavities and after the sterilization of the seat sections by the steam has been completed, a fluid is introduced into the cavities of the seat sections and another fluid is forced through the compartments around the seat sections to cool the outer as well as the inner surfaces of the seat sections. The steam is generated in a boiler which is heated electrically and a cylinder, containing a charge for the boiler, is provided with a piston for directing the water into the boiler, the piston being operated and the circuit connected with the boiler being closed at the commencement of the sterilizing part of the cycle of operation. On the completion of the sterilization of the seat sections, the valve is opened to fill the pump cylinder with a charge for the next sterilization, the valve also serving to connect with the interior of the seat sections to supply a cooling fluid thereto. Means are provided to prevent the closing of the circuit connected with the boiler and also to open a circuit connected with the motor operating the device when the fluid pressure at the valve is below normal.

Further objects of the invention are to arrange the elements in a small casing to complete a cycle of operation in all cases in a certain and definite manner when the normal operation of the doors and the seat sections is interfered with, as well as when the parts move without interference.

The invention furthermore comprehends a door opening and closing means which is connected with a device for operating the latter.

Additional objects of the invention will appear in the following specification in which the preferred form of the invention is described.

In the drawings similar reference characters refer to similar parts in all the views, of which

Figure 1 is a perspective view illustrating the sterilizer disposed at a toilet bowl with the doors opened and the seat sections de-

scending to a position spaced above the toilet bowl,

Figure 2 is a perspective view similar to the view illustrated in Figure 1, but with the doors closed and the seat sections spaced above the toilet bowl in position to be used,

Figure 3 is an enlarged front sectional elevation of the device,

Figure 4 is an enlarged fragmentary plan view of the device with its top removed,

Figure 5 is an enlarged sectional view on the line 5—5 of Figure 3,

Figure 6 is a sectional view on the line 6—6 of Figure 3,

Figure 7 is a sectional view on the line 7—7 of Figure 3,

Figure 8 is a fragmentary sectional view on the line 8—8 of Figure 3,

Figure 9 is an enlarged sectional view illustrating the door operating and locking mechanism,

Figure 10 is a transverse sectional view illustrating the compartments with the doors and the means for locking the compartments,

Figure 11 is a sectional view on the line 11—11 of Figure 9,

Figure 12 is a sectional view illustrating one of the seat sections with the valve means for directing a cooling fluid in an enclosed cavity in the seat section,

Figure 13 is a sectional view on the line 13—13 of Figure 12,

Figure 14 is an enlarged sectional view on the line 14—14 of Figure 13,

Figure 15 is a view illustrating the connections for directing steam into the compartments, and

Figure 16 is a diagrammatic view illustrating the electrical circuits and the means at a door for controlling the electrical circuits.

In the operation of the sterilizer, the doors are unlocked and opened, the seat sections are lowered to a position spaced above the bowl, at which time the doors are closed, and the seat sections are positioned for use. When the user sits on the seat sections they are pressed downwardly, setting mechanism which starts when the user leaves the seat sections, the said mechanism opening the doors for receiving the seat sections, when the doors are closed and a fluid, preferably steam, is introduced into the compartments to sterilize the seats, after which the seats are cooled by the introduction of a fluid into the cavities in the seat sections, at which time another cooling fluid is introduced into the compartments to cool the outer surfaces of the seat sections.

When the sterilizer is used with the construction illustrated in Figure 3 of the drawings, the button 20 is pushed inwardly, which operates the bell crank 21 to press the bell crank arm 22 downwardly, the said bell crank arm engaging a projection 23 on a lever 24 pivoted at 25. This movement of the lever 24

will move the arm 26 of the lever 24 downwardly to permit the mercury valve 27 to close under the influence of the spring 28. The bell crank 21 is held yieldingly in inoperative position by a spring 29 and the lever 24 is held yieldingly in the position illustrated in Figure 3 by a spring 30. It will be seen by again referring to Figure 3 of the drawings, that a spring-pressed hook 31 is mounted on a link 32 and it will, therefore, be understood that when the lever 24 has been moved downwardly, the spring-pressed hook 31 will engage a pin 33 on the lever 24 to hold said lever 24 downwardly, after the pressure against the button 20 has been removed.

The movement of the mercury valve 27 under the influence of the spring 28 serves to close a circuit connected with a motor 34 in a manner which will be subsequently described in full. This motor 34 has a shaft 35 on which there is a worm 36 which meshes with a worm wheel 37 secured to a shaft 38 journaled in bearings 39 which may be secured to the motor casing 34, there being a gear 40 secured to the shaft 38 which meshes with a gear 41 integral with a gear 42, which are mounted to rotate on the main shaft 43, the gear 42 meshing with a gear 44 which rotates on a shaft 45 and which is integral with a gear 46 meshing with a gear 47 secured for rotating with the main shaft 43. The main shaft 43 serves to rotate several cams, which will be subsequently described.

It will be seen by referring to Figure 3 of the drawings that the lever 24 has a finger 103 disposed in a depression 99 in a cam 97, the cam 97 being secured for rotating with the main shaft 43, as best illustrated in Figure 6. With the closing of the circuit at the mercury valve 27 the motor 34 is operated, which rotates the door cam 48' which is secured to the main shaft 43, this door cam 48' being best shown in Figures 6 and 9 of the drawings. The door cam 48' has two projections 49' and 50' which are spaced apart with a depression 51 between the projections, so that the projection 49' will serve to open the doors, the doors being permitted to close when the depression 51 reaches its operative position, and the doors will be again opened when the projection 50' reaches an operative position.

As will best be seen by referring to Figure 1 of the drawings, there are two sterilizing compartments 52 for the seat sections 53 and there are two doors 54, one for closing each of the compartments 52, the doors being hinged at the inner sides of the compartments 52. When the projection 49' reaches operative position it presses downwardly against a roller 55 which is journaled to a slide 56 disposed for moving in a guideway 57. There is a cavity 58 in the slide 56 in which there is disposed a spindle 59 which is secured to a plunger 60, the spindle 59 extending in a guideway 61 in the slide 56.

and there being a pin and slot connection 62 which permits a limited movement of the spindle 59 at its plunger 60 relatively to the slide 56. The plunger 60 is held yieldingly extended by means of a spring 63 which is disposed between the plunger 60 and a shoulder 64 in the slide 56. It will, therefore, be seen that a slide 56 will be pressed downwardly, when the roller 55 is engaged by the projection 49' and that, by this means, the plunger 60 will be pressed yieldingly downwardly.

The plunger 60 is positioned for engaging wrists 65 on stub shafts 66, the wrists 65 carrying arms 67 which have inwardly extending teeth 68, these teeth 68 being best shown in Figure 6 of the drawings. The teeth 68 mesh with beveled gears 69 which have shafts 70 for rotating therewith. Secured or keyed to the shafts 70 there are members 71 which are secured to the doors 54 for opening and closing the said doors, the shafts 70 serving as pintles for the doors. Wound around the shafts 70 there are springs 72 which are secured to the casing at 73 and to the shaft 70 to rotate the shafts yieldingly to move the doors to closed position. It will be seen from the above that the doors are opened and closed yieldingly and that should the normal movement of one or both of the doors be interfered with, the doors will quickly assume their normal positions when the interference is removed.

When the doors have been opened by the engagement of the projection 49' on the cam 48' with the roller 55, the two seat sections are moved outwardly from the compartments by the means which will now be described. The seat cam is best illustrated in Figures 3 and 6, this seat cam being referred to by the character 74. The seat cam has a projection 75, illustrated in Figure 3, the projection 75 being disposed for engaging a roller 76 mounted on a bracket 77, the bracket 77 being pivoted at 78 to a block 79. The block 79 moves in a guideway 80 and secured to the block 79 there is a rack 81 which engages teeth 82 on a lever 83 which has bearings 84 in which pins 85 are disposed, these pins 85 also extending in slots 86 in guide members 87, the guide members 87 being connected by arms 88 with racks 89 which are disposed for moving in guideways 90 and which mesh with hubs 91 secured to the seat sections, the hubs 91 being mounted on stub shafts 92.

There is also mounted on the pins 85 a yoke 93 which is connected with the frame by means of a spring 94. There are also springs 95 which are secured to the pins 85 and also to the pins 96 which connect the arms 88 with the racks 89.

It will be understood from the above that the spring 94, which has considerably more strength than the springs 95, will serve to hold the pins 85 yieldingly downwardly and

with the racks 89 in their lowermost positions, as illustrated in Figure 6. This position of the racks 89 by means of the hubs 91, will serve to hold the seat sections in the compartments until the cam projection 75 engages the roller 76, which will press downwardly the block 79 in the manner described, which will move the rack 81 downwardly and by means of the lever 83 will move the pins 85 upwardly. This upward movement of the pins 85 will, by the means described, move the racks 89 upwardly, which will rotate the seat hubs 91 and move the seat sections from within the compartments. The springs 95 serve to move the racks 89 yieldingly by the means described to give the seat sections 53 an initial outward movement from the compartments 52. The further downward movement of the seat sections will be regulated by the springs 94 and 95 and until the seat sections are disposed spaced above the bowl, as illustrated in Figure 2. When the seat sections are free from the compartments, the door cam 48' will move to a position where the depression 51 will be disposed at the roller 55, which will permit the doors to close.

There are two cams 97 and 98 secured for rotating with the shaft 43, the cams 97 and 98 being best shown in Figures 3 and 6 of the drawings. The cam 97 has two depressions 99 and 100 and the cam 98 has two depressions 101 and 102. When the button 20 was pressed inwardly to start the device, the finger 103 on the lever 24 was disposed in the depression 99 in the cam 97, but with the rotation of the cam 97 with the main shaft the finger 103 moved out of the said depression 99 and onto the periphery of the cam 97 between the depression 99 and the depression 100, this serving to hold the lever 24 out of engagement with the mercury valve 27 and serving to keep the circuit to the motor 34 closed independently of the button 20 and the bell crank 21. Another lever 104 is pivoted at 25, this lever 104 having a finger 105 which was disposed in the depression 101 in the cam 98 when the machine was first started. However, with the rotation of the main shaft 43, the cam 98 is rotated until the finger 105 is out of the depression 101 and against the outer surface of the cam 98 between its depression 101 and its depression 102. This movement of the lever 104 at its finger 105 is against the resiliency of a spring 106 and serves to move at its pin and slot connection 107 on the link 32. By this movement of the lever 104 the link 32 at its spring-pressed hook 31 is moved to the right and out of engagement with the pin 33. It will, therefore, be seen that when the finger 103 reaches the depression 100 in the cam 97, the spring 30 will move the said finger 103 into the depression, which will move the arm 26 of the lever 24 against the mercury valve 27 to open the mercury valve. The motor will then be

stopped with the doors closed and with the seat sections 53 disposed spaced above the bowl, as shown in Figure 2 of the drawings.

It will be seen by referring to Figures 3 and 6 of the drawings that extending downwardly from one of the arms 88 there is a pin 108 which is disposed for engagement with a lever 109 pivoted to the frame 110. This lever 109 is held yieldingly against a pin 111 by a spring 112, the lever 109 being articulated to the link 32 by a pin 113. The upward movement of the arms 88 with the downward movement of the seat sections serves to move the pin 108 into close engagement with the lever 109 and the pin 108 is so disposed in close engagement with the lever 109 when the seat sections are spaced above the bowl, as illustrated in Figure 2. With a further downward movement of the seat sections, when the seat is occupied, the pin 108 moves the lever 109 upwardly and through the link 32 the spring-pressed hook 31 is moved to operatively engage the pin 33 on the lever 24, but, the pin 108 serves to hold the lever 109 raised against the influence of the spring 112 and with the spring-pressed hook 31 in operative position, but not pressing down on the pin 33. However, when downward pressure against the seat sections is removed, the arms 88 are moved downwardly as the seat sections again assume the position illustrated in Figure 2 of the drawings, moving the pin 108 out of contact with the lever 109, so that the spring 112 serves to move the lever 109 against the pin 111, which, by means of the link 32 and the spring-pressed hook 31, presses downwardly against the pin 33 to move the lever 24 to a position where the mercury valve 27 is permitted to close under the influence of the spring 28. This closes the circuit to the motor and starts the device to complete its cycle of operation.

However, it will be understood that, if the user should remove pressure from the seat sections temporarily and should again exert downward pressure on the seat sections, the pin 108 will again be moved upwardly, which will serve, by the means described, to move the spring-pressed hook 31 upwardly to permit the lever 24 to again open the mercury valve 27.

With the continued operation of the device the finger 103 on the lever 24 moves out of the depression 100 in the cam 97, leaving the lever held in position out of operative engagement with the mercury valve 27 by means of the spring-pressed hook 31. However, when the finger 105 on the lever 104 moves out of the depression 102 in the cam 98, the lever 104 is operated and by the pin and slot connection 107 moves the link 32 to the right to free the spring-pressed hook 31 from the pin 33. During this period in the cycle of operation, the door cam

48' has been moved to bring its projection 50' into engagement with the roller 55 to open the doors and the cam 75 is moved off the roller 76, the spring 94 moving the yoke 93 downwardly and with it the pins 85 which press the guide members 87 downwardly, which serve to rotate the seat hubs 91 to move the seat sections into the compartments, when the projection 50' on the door cam 48' will pass beyond the roller 55 and permit the doors to close under the influence of the springs 72.

By referring to Figure 3 of the drawings, it will be seen that a link 114 is pivoted to the bracket 77 and another link 115 is pivoted to the block 79 and to these links 114 and 115 there is pivoted a link 116, the construction being in the nature of a toggle joint, the said link 116 being pivoted to a bell crank lever 117 which is held yieldingly by a spring 118, the bell crank lever 117 at 119 being articulated to a link 120 which has a bifurcated end 121 embracing a pin 122 on the mercury valve 27. It will be seen that, with this construction, when the cam 75 has passed beyond the roller 76, should the upward movement of the seat sections be interfered with, the spring 94 will, through the lever 83 and the rack 81, hold the block 79 downwardly, which will operate the bell crank lever having the links 114 and 115, to move the bracket 77 so that the roller 76 will engage the cam wheel 74 beyond its projection 75, which will move the link 116 inwardly, operating the bell crank 117 to press the link 120 upwardly to move, by the means described, the mercury valve 27 to open position until the interference with the seat sections is removed.

When the seat sections have been moved into the compartments 52 and the doors 54 have been closed under the influence of the springs 72, the doors are locked to prevent the escape of the steam which is used in sterilizing the seat sections, and also to prevent the opening of the doors during the sterilizing process, which might cause injury to the user. Each of the doors has a flange 123, as best shown in Figure 10 of the drawings and these flanges are positioned for engagement by locking hooks 124, the locking hooks 124 being disposed for movement in guideways 125 and having rollers 126 mounted on pins 127 which are disposed for moving in slots 128 in the guideways 125. It will therefore be seen that the hooks 124 may move inwardly and outwardly and that the hooks 124 also may have a limited rotary movement at their pins 127. Springs 129 are provided for holding the hooks 124 yieldingly in the positions illustrated in Figure 10 of the drawings.

The guideways 125 have shoulders 130, there being cam rods 131 which are disposed for movement between the shoulders 130 and the rollers 126 for pressing the rollers 126 130

inwardly to draw inwardly the hooks 124 for pressing inwardly the doors 54 at their flanges 123. When the cam rods 131 are moved in the direction of each other, the pins 132 move the hooks 124 against the resiliency of the springs 129 to move the hooks clear of the flanges 123. The cam rods 131 telescope, one within the other, as illustrated in Figures 9 and 10 of the drawings, and each of the cam rods 131 has a shoulder 133, there being a spring 134 on the cam rods 131 disposed between their shoulders 133 to hold the cam rods 131 yieldingly extended. Each of the cam rods has a slot 135, there being knuckles 136 disposed in these slots 135, the knuckles 136 being integral with bell cranks 137 which are pivoted at 138, one of the bell cranks 137 having a roller 139 for traveling in a cam groove 140 in the door cam 48 and being connected by a projection 141 having a roller 142 engaging a finger 143 on the other bell crank 137.

It will be understood that the locking means is held yieldingly in operative position by means of the spring 134 and that, when the roller 139 rides in the groove 140 of the door cam 48 at its portion 144^a through the bell cranks 137, the cam rods 131 will be moved inwardly. These cam rods 131 are moved inwardly prior to the opening of the doors and they remain in inoperative position during the period that the doors are closed while the seat sections are disposed at the bowl and when the doors are again opened and the seat sections are moved into the compartments, after which the doors are closed for the sterilizing process, the doors being locked during the sterilizing process to prevent the escape of steam and injury to a user by the possible opening of the doors. It is important that the doors be in closed position when the cam rods 131 are moved outwardly to lock the doors in the manner described.

Pins or members 144 are disposed for moving in guideways 145 in the casing at the door openings, these pins or members 144 being disposed for engagement by the doors. These pins extend outwardly from arms 146 on collars 147 which are rotatably mounted on a shaft 148 journaled in bearings 149' in the frame. Extending from the collars 147 there are members 149 having bearings 150 engaging a lever 151, the lever 151 being pivoted to a standard 152 on a collar 153 keyed to the shaft 148. With this construction it will be understood that should only one of the arms 146 be moved rearwardly by a pin or member 144, it will rotate the lever 151 on its pivot, which will not rotate the collar 153, but when both arms are moved rearwardly by the pins 144, the collar 153 will be rotated by the lever. This collar 153 has a finger 154 which is disposed for entering a depression 155 in the door cam 48', which is shown in Figure 9 of the drawings. There

is a spring 155 secured to the shaft 148 which serves to hold the shaft 148 yieldingly with the finger 154 pressed against the face of the door cam 48' and it will, therefore, be seen that, if the arms 146 are not pressed inwardly by the pins or members 144, the finger 154 will move into the depression 155 in the door cam 48' when the finger reaches the said depression, which is immediately before the sterilizing period in the cycle of operation.

The shaft 148 is bent at the spring 155, as best shown in Figure 11 of the drawings, and the bent terminal of this shaft 148 is disposed at the pin 156 of the mercury valve 27 for opening the mercury valve 27 when the finger 154 enters the depression 155^a in the door cam 48'. It will, therefore, be understood that when the pins or members 144 are not pressed inwardly at the commencement of the period of sterilization in the cycle of operation, the motor will be stopped and the operation of the sterilizer will be interrupted until the doors are permitted to close, when the inward pressure against the pins or members 144 will, by the means described, move the finger 154 out of the depression 155^a in the door cam 48' to move the bent arm of the shaft 148 to permit the mercury valve 27 to close under the influence of the spring 28.

In order to guard against the possibility of the user, through curiosity, pressing inwardly the pins or members 144 with the doors open, pins 157 project from the members 149 to be engaged by cams 158 on the door pintles 159, which are in alignment with the shafts 70 shown in Figure 9 of the drawings. The door knuckles 160 are secured to the door pintles 159, the door pintles being disposed in bearings 161 on the frame. The cams 158 are disposed to engage the pins 157 and prevent the collars 147 from rocking the collar 153 through the lever 151 when the doors are in open position.

The boiler, which is used in the generation of the steam for the sterilization of the seat sections in the compartments, is referred to by the reference characters 162 in Figure 3 of the drawings, this steam generator being shown in detail in applicant's United States patent application which was filed on August 23rd, 1930 and which bears Serial No. 477,433. The outlet pipe 163 from the boiler 162 is best shown in Figure 15 of the drawings and it will be seen that this outlet pipe 163 has branches 164 leading to the compartments respectively, each branch 164 having a plurality of outlets 165 which, as best shown in Figures 10 and 11, are provided with baffles 166 which serve to direct the steam laterally in all directions at each outlet 165 in the compartments.

The boiler 162 is supplied with a charge of water which is contained in a cylinder 167 by the connecting pipe 168 leading from the bottom of the cylinder 167 to the boiler 162.

162. There is a piston 169 in the cylinder 167 having a piston rod 170, the piston rod 170 having an opening 171 in which is disposed a knuckle 172 on a lever 173, the lever 173 having a roller 174 which travels in a cam groove 175 in the cam 74 keyed to the main shaft 43, the lever 173 being mounted for rocking at 176 on the shaft 45. It will, therefore, be seen that during each cycle of operation, the piston 169 will be forced downwardly to supply the boiler 162 with a charge of water and at the end of the sterilizing process the piston 169 will be raised in the cylinder 167 to draw into the cylinder 167 steam and vapor from the boiler 162, at which time the cylinder 167 is supplied with a charge of a fluid for the next sterilizing process.

As will best be seen by referring to Figures 3 and 15 of the drawings, a pipe 177 connects a valve 178 with the cylinder 167, this said valve 178 having a valve stem 179 which is engaged by an arm 180 on a lever 181 which is mounted to rock at 182 on the shaft 45, as best shown in Figure 6 of the drawings. This lever 181 has a roller 183 which travels in a cam groove 184 in the gear 47. Therefore, by the said means the valve stem 179 will be operated with the rotation of the main shaft 43 and the gear 47.

The valve 178, which is best shown in Figure 3 of the drawings, has two valve seats 185 and 186, the valve stem 179 being provided with a valve 187 commanding the valve seat 185 and there being a valve 188 commanding the valve seat 186, the valve 188 having a valve stem 189 around which there is a spring 190 which serves to hold the valve 188 yieldingly on its seat 186. Extending beyond the valve 188 there is a member 191 with radially extending vanes which permit a fluid to pass through the valve seat 186 when the valve 188 is moved downwardly from the valve seat 186 by the valve stem 179 which extends below the valve 187.

As has been stated, the valve 178 is connected with the cylinder 167 by the pipe 177. A water inlet 192 leads to the valve 178 at a lateral extension 193 of the valve which is disposed in the chamber below the valve seat 186. It will, therefore, be understood that when the valve stem 179 is moved downwardly through the movement of the lever 181 and the roller 183 in the cam groove, water will be permitted to flow through the valve seat 186 and, if the valve stem is moved to its lowermost position, the water will also flow through the valve seat 185 and through the pipe 177 to the cylinder 167. Therefore, during each cycle, the cylinder 167 is supplied with a charge of water through the valve 178, the water passing through the inlet 192 through the valve seats 186 and 185, in the manner described, to the cylinder.

The valve 178 also has an outlet 194 in the

chamber between the valve seats 185 and 186, the outlet 194 being connected with a pipe 195 which is connected to the means for introducing water into the inclosed cavities in the seat sections for cooling the seat sections after they have been sterilized by steam in the compartments.

As a means to stop the operation of the sterilizer, when the water pressure at the valve 178 falls below a predetermined point, a bellows 196 is connected to the lateral extension 193 on the valve 178 and engaging this bellows 196 there is an arm 197 of a lever 198 which is pivoted at 199, the lever 198 being held with its arm 197 against the bellows 196 by means of a spring 200. Articulated to the lever 198 there is a link 201 which has an arm 202 disposed at the mercury valve 27 for opening the mercury valve 27 against the resiliency of the spring 28 when the bellows 196 moves inwardly through lack of pressure in the valve 178. The link 201 also extends to a mercury valve 203, which, as will be subsequently described, opens and closes the circuit connected with the boiler 162. By this means, not only will the operation of the sterilizer be stopped, when the water pressure at the valve 178 falls below a certain point, but the circuit connected with the boiler 162 will also be opened.

As has been stated, the mercury valve 203 serves to open and close the circuit leading to the boiler 162, a spring 204 being provided for holding the mercury valve 203 yieldingly closed. The closure of the mercury valve 203 is prevented by a cam 205 on a link 206 before and after the sterilizing period in the cycle of operation, this link 206 being articulated at 207 to a lever 208 which is pivoted at 209 to the casing, the lever 208 having a roller 210 which travels in a cam groove 211 in the main gear 47. It will be understood that when the roller 210 moves into the depressions 212 in the cam groove 211, the depressions being shown in Figure 3 of the drawings, the link 206 will move downwardly to move its cam 205 below the roller 212^a on the mercury valve 203, thereby permitting the mercury valve 203 to close under the influence of its spring 204. The mercury valve 203 remains closed during the sterilizing period.

At the completion of the sterilizing period, the surface 213 in the cam groove 211 will engage the roller 210 to move the link 206 upwardly to open the mercury valve 203. the continued upward movement of the link 206 pressing upwardly the bifurcated terminal 214 of the link 206, this bifurcated terminal 214 embracing a pin 215 on a lever 216 which is secured to an air valve 217 pivoted at 218 in a compartment 219 at the top of the casing.

There are two of these air valves 217, one of the air valves 217 being operated in the

manner described and the other air valve 217 being operated through a link 220 which connects an arm 221 on the lever 208 with the other lever 216, the link 220 having a bifurcated terminal 22 which embraces the pin 215. It will, therefore, be seen that when the link 206 has moved downwardly, it opens the mercury valve 203 to close a circuit leading to the boiler 162 and when the lever 208 is moved 10 upwardly it opens both air valves 217.

As will best be seen by referring to Figure 7 of the drawings, these air valves 217 control communication from the air compartment 219 to the compartments 52 and air is forced by 15 the fan 223, secured to the shaft 35 of the motor 34, through the ports controlled by the valves 217 into the compartments. This air enters the casing through a rear opening 224 which is provided with vanes 225 which are 20 spaced apart and which extend inwardly and upwardly to prevent dirt from collecting on the vanes, which may be drawn into the casing, the air passing to the compartment 219 at the rear of the compartments 52 through an 25 opening 226 above the compartment 219. This opening 226 extends preferably in a lid 227 which is disposed for closing the top of the casing.

At the end of the sterilizing period in the 20 cycle of operation, and when the air valves 217 have been opened, water is introduced into the cavities in the seat sections through the valve seat 186 and the port 194 in the valve 178, the valve stem 179 being sufficiently depressed to permit the water to flow through 25 the valve seat 186 after the cylinder 167 has been filled with a charge of water for the next sterilizing period and when the valve 187 has again been moved to a position where it closes 30 the port 185. As has been stated, this water flows from the port 194 through the pipe 195, the pipe 195 leading to a valve 228 having an inlet port 229, two ports 230 and an outlet 231, the outlet 231 being disposed above a portion 35 of the bottom of the casing leading to the drain 233, which is disposed above the bowl of the toilet. In the valve casing there is a valve 234, there being a spring 235 for pressing the valve 234 with its head 236 against the port 40 229, the head 236 being preferably provided with an aperture 237 to permit the head 236 of the valve 234 to move readily away from the port 229 under the influence of the water passing through the pipe 195. This valve 234 is 45 also provided with ports 238 which communicate with the ports 230 in the valve casing when the valve 234 is in its closed position.

Pipes 239 connect the ports 230 in the valve casing with passages 240 in the members on 50 which the seat sections are pivoted and there are passages 241 in the seat sections which lead to cavities 242 therein, the said passages 241 being positioned to afford communication between the passages 240 and the cavities 242 55 when the seat sections are disposed vertically

and in the compartments 52. In the cavities 242 in each seat section there is a pipe 243 which communicates with a passage 244 in the seat section leading to a passage 245 in the members on which the seat sections are pivoted, the said passages 245 in the said members leading to outlets 246 to the portions 232 at the bottom of the casing. It will, therefore, be understood that when the seat sections have been sterilized in the compartments 52, the water pressure in the pipe 195 will press the head 236 of the valve 234 away from the port 229 and permit the water flowing in the pipe 195 to pass through the ports 238 and through the ports 230 to the pipes 239 and into the cavities 242 in the seat sections, the water passing out of the cavities 242 through the pipes 243 to the outlets 246. When the flow of water through the pipe 195 has been discontinued through the closing of the valve seat 186, the valve 234 will move to the position indicated in Figure 14 of the drawings, and all water contained in the cavities 242 will flow through the passages 241 to the passages 240, and thence through the ports 230 and 238 and out of the outlet 231 to the drain 233. Therefore, when the sterilization of the seat sections has been completed, not only will the outer surfaces of the seat sections be cooled by the air passing through the compartments 52, but the inner surfaces of the seat sections will be cooled by the water passing therein.

When the air valves 217 have been closed by the movement of the lever 208, a link 247, which is best shown in Figures 3 and 8 of the drawings, and which has a pin and slot connection 248 with the lever 208, is moved downwardly by the lever 208. Secured to this link 247 there is a rack 249 which moves in a guide-way 250, the teeth of the rack 249 meshing with the teeth 251 secured to the rotary valves 252 which are disposed at the bottom and at the rear of the compartments 52. These rotary valves 252 are cylindrical, with passages 253 therein, there being apertures 254 in the valves 252 which permit the waters of condensation to pass from the compartments into the passages 253 in the valves 252 when the valves 252 are closed. The said valves 252 have outlet ports 255 which are disposed adjacent the portion 232 of the casing and which lead to the drain 233. These valves 252 permit not only the escape of the waters of condensation, but also when they are open, the air which has been directed into the compartments 52 at the valves 217. This completes the cycle of operation, when the finger 103 will be disposed in the depression 99 in the cam 97 and the finger 105 will be disposed in the depression 101 in the cam 98.

By referring to Figure 16 of the drawings, it will be seen, where the circuits are shown diagrammatically, that a wire 256 leads to the motor 34 and through a wire 257 to the boiler 162, a wire 258 leading from the motor 34 to a

wire 259 (shown in dotted lines) and to the mercury valve 27, a wire 260 leading from the mercury valve 27 to the mercury valve 203, a wire 261 leading from the wire 260 to the wire 262, a wire 263 leading from the mercury valve 203 to the boiler 162. It will, therefore, be understood that when the mercury valve 27 is closed, a current will pass through the motor to operate the latter and that when the 10 mercury valve 203 is closed, a current will pass through the boiler 162 to heat the latter.

Not only may the sterilizer be used by pressing the button 20, but, as will be seen by referring to Figure 16 of the drawings, the 15 sterilizer may be used by another means which may be secured to a door. When this is the case, the button 20 and the bell crank 21 may be dispensed with, and the wire 259, which is shown in dotted lines in Figure 16 20 of the drawings, will also be omitted. In this arrangement, a lever 264 is secured to a door handle, and when the door handle is rotated to open the door, its lever 264 is moved in the direction of the arrow and the spring 265 on 25 the lever will engage a stud 266 on a mercury valve 267, the engagement of the spring 265 with the stud 266 serving to close the mercury valve 267, and the finger 268 on a spring-pressed lever 269 entering a recess 270 on a 30 disc 271 carrying the stud 266, which holds the mercury valve 267 closed against the resiliency of a spring 272. A current will then flow from the wire 256 through the motor 34, through the wires 258 and 258^a to the wire 35 272, through a resistance 274^a to the mercury valve 267 and to the wire 262. This will operate the motor until the fingers 103 and 105 move out of the recesses 99 and 101 in the cams 97 and 98 respectively. The continued 40 operation of the sterilizer will then proceed in accordance with the description which has been outlined above.

It will be understood that the lever 264 may pass beyond the stud 266, its spring 265 serving 45 to operate the mercury valve 267, the mercury valve being held in operative position by the means described and the arm 264 may pass through an arc of approximately 180°.

There is a stop 274 which is positioned for 50 engagement by the finger 268 which limits the rotary movement of the mercury valve 267 when the finger 268 is moved away from the recess 270. It will be understood that during the cycle of operation, current will not 55 only flow through the wire 258^a to the wire 273, but current will also flow through the wire 258^a, through the solenoid 275 to the wire 276 and to the mercury valve 27 which has been closed as stated above. This will 60 energize the solenoid 275 to move its armature 277 in the direction of the arrow and against the resiliency of the spring 278 to press outwardly the arm 279 of the lever 269, which will move the lever 269 out of the recess 270 and permit the mercury valve 267 to move to

open position under the influence of its spring 272. The wires 258^a and 276 will, however, still be connected through the solenoid 275.

It is possible that someone may open the door, which will start the operating mechanism in the manner described, until the seat sections are spaced above the bowl, as shown in Figure 2 of the drawings, and without using the toilet the said person may open 70 the door and pass out. It is, therefore, necessary to provide means for completing the cycle of operation in such a case. This means consists of a member 280 which is secured to the means for opening the door from the inner side, this member 280 having an arm 281 which is articulated to a link 282, the link 282 having a pin and slot connection 283 with a disc 284 to which a mercury valve 285 is secured, the mercury valve 285 being held 80 yieldingly in open position by a spring 286. It will be understood that, by the means described, should the inner door handle be operated to open the door, a circuit will be closed leading from the motor 34 to the wires 258 and 258^a to the solenoid 275, a wire 287 to the mercury valve 285, and a wire 288 from the mercury valve 285 to a switch member 289, this switch member 289 being not only shown in Figure 16 of the drawings, but also 90 in Figure 3 of the drawings, and being positioned for movement by one of the guide members 87 when the seat sections are disposed above the bowl, as illustrated in Figure 2 of the drawings, to contact with a stationary switch member 290. This switch will 95 connect the wire 288 with the wire 291 which leads to the wire 261 connected with the wire 262.

This current will energize the solenoid 275 100 which will move the arm 292 to operate the lever 293 so that the finger 294 on the said lever 293 will engage the recess 295 on the disc 284. This will close the circuit through the motor 34 and with the operation of the motor, 110 and through the means described, the motor will serve to drive the mechanism until the finger 103 of the lever 104 has passed beyond the recess 100 in the cam 97, when the valve 27 will be closed and the motor will be energized through the solenoid 275 to the wire 276. At the complete termination of the cycle of 115 operation the mercury valve 27 will be opened in the manner described, which will deenergize the solenoid 275 and permit the mercury valve 284 to open to the position indicated in Figure 16 of the drawings.

What is claimed is:

1. In a sterilizer, two compartments, two seat sections movable relatively to each other, two doors for closing the compartments respectively, means for moving the seat sections yieldingly into and out of the compartments, means for yieldingly opening and closing the doors, and means for operating the

first and second mentioned means which will at times delay the closing of the doors until both seat sections are within the compartments.

2. In a sterilizer, a compartment means, a closure means for the compartment means, a seat, means for moving the seat yieldingly into and out of the compartment means for opening and closing the closure means, and 10 means for operating the first and second mentioned means which will at times delay the closing of the closure means until the seat is within the compartment means.

3. In a sterilizer, a seat, means connected 15 with the seat for operating the latter, a guide means secured to the first mentioned means, a member in the guide means, resilient means for holding the member yieldingly in the guide means, resilient means connecting the member with the first mentioned means, and 20 means for moving the member in the guide means.

4. In a sterilizer, a seat, means connected with the seat for moving the latter, two guide 25 members, each having a slot, the guide members being secured to the said means, a member extending in the slots, resilient means for holding the member yieldingly relatively to the guide members, a second resilient means 30 for holding the member yieldingly relatively to the first mentioned means, and means for moving the member in the slots in the guide members.

5. In a sterilizer, two seat sections, two 35 means for moving the seat sections respectively, two guide members, each with a slot, the guide members being secured to the said two means respectively, a member extending in the slots, resilient means for holding the 40 member yieldingly in the slots, additional resilient means connecting the third mentioned member with the first two mentioned means respectively, and means for moving the member in the slots in the guide members.

45 6. In a sterilizer, an operating cam, a block, a bracket normally engaging the block and movable relatively thereto, a member on the bracket for engaging the cam, a seat, means cooperating with the block and the seat for 50 moving the seat, means including an electric motor and a circuit for moving the operating cam, an extensible member connecting the bracket and the block, and means operable by the extensible member for opening and closing the circuit.

7. In a sterilizer, an operating cam, a block, a bracket normally engaging the block and movable relatively thereto, a member on the bracket for engaging the operating cam, a 55 toilet seat, means cooperating with the block and the toilet seat for moving the toilet seat, means including an electric motor and a circuit for moving the operating cam, a toggle joint connecting the bracket and the block,

and means operable by the toggle joint for opening and closing the circuit.

8. In a sterilizer, a toilet seat, means for moving the toilet seat, a guide means secured to the first mentioned means, a member 70 in the guide means, resilient means for holding the member yieldingly in the guide means, a resilient means connecting the member with the first mentioned means, an operating cam, a block, a bracket normally engaging the block and movable relatively thereto, a member on the bracket for engaging the cam, means connecting the block with the member for moving the latter in the guide means, means including an electric motor and a circuit for moving the operating cam, an extensible member connecting the bracket and the block, and means operable by the extensible member for opening and closing the circuit. 75

9. In a sterilizer, a toilet seat, means for moving the toilet seat, a guide means secured to the first mentioned means, a member in the guide means, resilient means for holding the member yieldingly in the guide means, 90 a resilient means connecting the member with the first mentioned means, an operating cam, a block, a bracket normally engaging the block and movable relatively thereto, a member on the bracket for engaging the cam, 95 means connecting the block with the member for moving the latter in the guide means, means for moving the operating cam, an extensible member connecting the bracket and the block, and means operable by the extensible member for rendering the sixth mentioned means inoperative. 100

10. In a sterilizer, a toilet seat, means to move the toilet seat in one direction, means to operate the first mentioned means, means 105 cooperating with the first mentioned means to set the second mentioned means for operation when the toilet seat moves in another direction, the third mentioned means controlling the operation of the second mentioned means through the positioning of the seat. 110

11. In a sterilizer, a toilet seat, means to move the toilet seat including a member having a projection, means to operate the first 115 mentioned means including an electric motor with a circuit, and means positioned for engagement by the projection for opening the circuit when the projection is in one position and for closing the circuit when the 120 projection is in another position.

12. In a sterilizer, a toilet seat, means to move the toilet seat including a block and a member having a projection, a cam, a member movably mounted on the block for engaging the cam, means to operate the cam, including an electric motor with a circuit, 125 means positioned for engagement by the projection for opening and closing the circuit, an extensible member connecting the second 130

mentioned member and the block, and means operable by the extensible member for opening and closing the circuit.

13. In a sterilizer, a circuit, a switch in the circuit, means for holding the switch yieldingly closed, a lever positioned to engage the switch to open the latter, a pin on the lever, a link, a hook on the link for engaging the pin to hold the lever when it has been moved to permit the switch to close, a toilet seat, means to move the toilet seat, means for operating the second mentioned means including an electric motor in the circuit, means driven by the third mentioned means to free the hook from the pin, thereby permitting the switch to open, means operable by the second mentioned means to move the link to again engage the hook with the pin, the positioning of the toilet seat thereafter serving, through the second and fifth mentioned means, to open the switch and permit the switch to close.

14. In a sterilizer, a circuit, a switch in the circuit, means for holding the switch yieldingly closed, a lever positioned to engage the switch to open the latter, a pin on the lever, a link, a hook on the link for engaging the pin to hold the lever when it has been moved to permit the switch to close, a toilet seat, means to move the toilet seat, means for operating the second mentioned means including an electric motor in the circuit, means driven by the third mentioned means to free the hook from the pin, thereby permitting the switch to open, means operable by the second mentioned means to move the link to again engage the hook with the pin, the positioning of the toilet seat thereafter serving, through the second and fifth mentioned means to open the switch and permit the switch to close, the fourth mentioned means serving to free the lever from the switch when the motor, which has been again started, has run a predetermined time.

45 15. In a sterilizer, a circuit, a switch in the circuit, an electric motor in the circuit, means for closing the switch, a toilet seat, means for moving the toilet seat, means by which the electric motor is adapted to operate the second mentioned means, means cooperating with the third mentioned means for opening the switch and permitting the switch to close, and means cooperating with the second mentioned means for opening the switch.

55 16. In a sterilizer, a circuit, a switch in the circuit, an electric motor in the circuit, means for closing the switch, a toilet seat, means by which the electric motor is adapted to operate the second mentioned means, means cooperating with the third mentioned means for opening the switch and permitting the switch to close, means cooperating with the second mentioned means for opening the switch, and means cooperating with the second men-

tioned means for opening the switch when the movement of the toilet seat by the second mentioned means is interfered with.

17. In a sterilizer, a circuit, a switch in the circuit, an electric motor in the circuit, means for closing the switch, a toilet seat, means for moving the toilet seat, means cooperating with the electric motor and the second mentioned means for operating the latter, means for opening the switch, means cooperating with the third and fourth mentioned means for operating the latter, and means for moving the fourth mentioned means into inoperative position.

18. In a sterilizer, a motor having a circuit, a toilet seat, means cooperating with the motor and the toilet seat for moving the latter, a pin on the said means, a pivoted lever disposed in the path of the pin, and means for opening and closing the circuit operable by the lever.

19. In a sterilizer, a motor having a circuit, a toilet seat, means cooperating with the motor and the toilet seat for moving the latter, a pin on the said means, a pivoted lever disposed in the path of the pin, means for opening and closing the circuit operable by the lever, and means for holding the lever yieldingly in a predetermined position.

20. In a sterilizer, a motor having a circuit with a switch, a toilet seat, a block, means cooperating with the block and the toilet seat for moving the latter, a cam means operable by the motor, a member movably mounted on the block and engaging the cam, two links pivoted to the block and to the member respectively, a third link pivoted to the said two links, a lever pivoted to the third link, and means cooperating with the lever and the switch for controlling the latter.

21. In a sterilizer, a motor with a circuit and a switch, a door, means cooperating with the motor and the door for moving the latter, means for moving the switch into one position, a lever for moving the switch into another position, and means cooperating with the first mentioned means and the lever for moving the latter.

22. In a sterilizer, a motor with a circuit and a switch, a door, means cooperating with the motor and the door for moving the latter, a lever for moving the switch into a predetermined position, and a cam driven by the said means and engaged by the lever for operating the latter.

23. In a sterilizer, a motor with a circuit and a switch, a door, means cooperating with the motor and the door for moving the latter, a lever for moving the switch into a predetermined position, and a cam engaged by the lever for normally holding the lever with the switch in the said position, the cam having surfaces in the path of the lever for peri-

odically moving the lever to permit the switch to move to another position.

24. In a sterilizer, a motor and a circuit with a switch, a door, means cooperating with the motor and the door for moving the latter, a lever for moving the switch into a predetermined position, two cams driven by the first mentioned means, one of the cams being engaged by the lever for operating the latter, a pin on the lever, a second lever engaging the other cam to be operated thereby, and a spring-pressed means operated by the second mentioned lever for engaging the pin.

25. In a sterilizer, a motor and a circuit with a switch, a door, means cooperating with the motor and the door for moving the latter, a lever for moving the switch into a predetermined position, two cams driven by the first mentioned means, one of the cams being engaged by the lever for operating the latter, a pin on the lever, a second lever engaging the other cam to be operated thereby, a spring-pressed means operated by the second mentioned lever for engaging the pin, and additional means for operating the first mentioned lever which serves to move the pin for engagement by the spring-pressed means.

26. In a sterilizer, a motor with a circuit and a switch, a seat, means cooperating with the motor and the seat for moving the latter, a lever for moving the switch into a predetermined position, two cams driven by the said means, one of the cams being engaged by the lever for operating the latter, a pin on the lever, a second lever engaging the other cam to be operated thereby, a spring-pressed means operated by the second mentioned lever for operatively engaging the pin, and means cooperating with the first mentioned means and the spring-pressed means for moving the latter to operatively engage the pin by the hook.

27. In a sterilizer, a motor with a circuit and a switch, a seat, means cooperating with the motor and the seat for moving the latter, a lever for moving the switch into a predetermined position, two cams driven by the said means, one of the cams being engaged by the lever for operating the latter, a pin on the lever, a second lever engaging the other cam to be operated thereby, a spring-pressed means operated by the second mentioned lever for operatively engaging the pin, means cooperating with the first mentioned means and the spring pressed means for moving the latter to operatively engage the pin by the hook, and a fourth means for operating the first mentioned lever, which serves to move the pin for engagement by the hook.

28. In a sterilizer, a motor with a circuit and a switch, a seat, means cooperating with the motor and the seat for moving the latter, a pin on the said means, a lever for moving the switch into a predetermined position, cam

means driven by the first mentioned means, the cam means being engaged by the lever for operating the latter, a pin on the lever, a second lever engaged by the cam means to be operated thereby, a link pivoted to the second mentioned lever, a spring-pressed hook on the link for operatively engaging the second mentioned pin, a third lever disposed in the path of the first mentioned pin, the third lever being pivoted to the link.

29. In a sterilizer, a motor with a circuit and a switch, a seat, means cooperating with the motor and the seat for moving the latter, a pin on the said means, a lever for moving the switch into a predetermined position, cam means driven by the first mentioned means, the cam means being engaged by the lever for operating the latter, a pin on the lever, a second lever engaged by the cam means to be operated thereby, a link pivoted to the second mentioned lever, a spring-pressed hook on the link for operatively engaging the second mentioned pin, a third lever disposed in the path of the first mentioned pin, the third lever being pivoted to the link, and manually operable means for operating the first mentioned lever.

30. In a sterilizer, two compartments, two doors for closing the compartments respectively, two stub shafts secured to the doors for opening and closing the latter, resilient means for rotating the stub shafts, gears on the stub shafts, two pivoted arms with teeth for engaging the gears, wrists on the arms, a plunger for engaging the wrists to rock the arms and thereby rotate the stub shafts, and means to operate the plunger.

31. In a sterilizer, two compartments, two doors for closing the compartments respectively, two stub shafts secured to the doors for opening and closing the latter, resilient means for rotating the stub shafts, gears on the stub shafts, two pivoted arms with teeth for engaging the gears, wrists on the arms, and a plunger for engaging the wrists to rock the arms and thereby rotate the stub shafts to open the doors.

32. In a sterilizer, two compartments, two doors for closing the compartments respectively, two stub shafts secured to the doors for opening and closing the latter, resilient means for rotating the stub shafts, gears on the stub shafts, two pivoted arms with teeth for engaging the gears, wrists on the arms, a plunger for engaging the wrists to rock the arms and thereby rotate the stub shafts to open the doors, and resilient means for pressing the plunger against the wrists.

33. In a sterilizer, two compartments, two doors for closing the compartments respectively, two stub shafts secured to the doors for opening and closing the latter, resilient means for rotating the stub shafts, gears on the stub shafts, two pivoted arms with teeth for engaging the gears, wrists on the arms, a

plunger for engaging the wrists to rock the arms and thereby rotate the stub shafts to open the doors, the plunger having a stem, a casing having a guide in which the stem is disposed, a spring around the stem between the casing and the plunger, and means to move the casing periodically.

34. In a sterilizer, two compartments, two doors for closing the compartments respectively, two stub shafts secured to the doors for opening and closing the latter, resilient means for rotating the stub shafts gears on the stub shafts, two pivoted arms with teeth for engaging the gears, wrists on the arms, a plunger for engaging the wrists to rock the arms and thereby rotate the stub shafts to open the doors, the plunger having a stem, a casing having a guide in which the stem is disposed, a pin and slot connection between the stem and the casing to limit the movement of the plunger relatively to the casing, a spring around the stem between the casing and the plunger, and means to move the casing periodically.

35. In a sterilizer, a motor with a circuit, a compartment means, a closure means for the compartment means, means operable by the motor for sterilizing the compartment means at a predetermined time, and means for opening the circuit at the said predetermined time when the closure means is opened.

36. In a sterilizer, a motor with a circuit, a compartment means, a closure means for the compartment means, means operable by the motor for sterilizing the compartment means at a predetermined time, means for opening the circuit at the said time, and means cooperating with the closure means and the compartment means to render the fourth mentioned means inoperative.

37. In a sterilizer, a motor with a circuit, a compartment means, a closure means for the compartment means, means operable by the motor for sterilizing the compartment means at a predetermined time, means for opening a circuit at the said time, a member at the compartment means for engagement by the closure means, and means cooperating with the member and the fourth mentioned means for rendering the fourth mentioned means inoperative.

38. In a sterilizer, a motor with a circuit, a compartment means, a closure means for the compartment means, means operable by the motor for sterilizing the compartment means at a predetermined time, means for opening a circuit at the said time, a member at the compartment means for engagement by the closure means, means cooperating with the member and the fourth mentioned means for rendering the fourth mentioned means inoperative, and means operative while the door is open to prevent the member from rendering the fourth mentioned

means inoperative through the fifth mentioned means.

39. In a sterilizer, a motor with a circuit, a compartment means, a seat movable into and out of the compartment means, a closure means for the compartment means, means operable by the motor for sterilizing the compartment means at a predetermined time, means for opening a circuit at the said time, a member at the compartment means for engagement by the closure means, means cooperating with the member and the fourth mentioned means for rendering the fourth mentioned means inoperative, and means operative while the door is open to prevent the member from rendering the fourth mentioned means inoperative through the fifth mentioned means.

40. In a sterilizer, a motor with a circuit, two compartments, doors for closing the compartments, means operable by the motor for sterilizing the compartments at a predetermined time, a disc with a depression, means connecting the first mentioned means with the disc for moving the latter, a shaft, a collar keyed to the shaft, the collar having a finger for engaging the disc to move into the depression at the said time, two collars mounted to rock on the shaft, two members, one at each compartment to be engaged by the doors when the doors are closed, means by which the members are adapted to rock the said two collars respectively, means by which the said two collars are adapted to rock the first collar and the shaft, and means by which the shaft is adapted to open the circuit when the finger moves into the depression in the disc.

41. In a sterilizer, a motor with a circuit, two compartments, doors for closing the compartments, means operable by the motor for sterilizing the compartments at a predetermined time, a disc with a depression, means connecting the first mentioned means with the disc for moving the latter, a shaft, a collar keyed to the shaft, the collar having a finger for engaging the disc to move into the depression at the said time, two collars mounted to rock on the shaft, two members, one at each compartment to be engaged by the doors when the doors are closed, means by which the members are adapted to rock the said two collars respectively, a stud mounted on the first mentioned collar, a lever pivoted to the stud for engagement with members on the said second and third mentioned collars, and means by which the shaft is adapted to open the circuit when the finger moves into the depression in the disc.

42. In a sterilizer, a motor with a circuit, a compartment, a door for the compartment, means for sterilizing the compartment at a predetermined time, means cooperating with the motor and the first mentioned means for operating the latter, means for closing the

- door, a member at the compartment for engagement by the door, and means cooperating with the member and the circuit for opening the latter at the said time when the door is not in engagement with the member. 5
43. In a sterilizer, a motor with a circuit, a compartment, a door for the compartment, means for sterilizing the compartment at a predetermined time, means cooperating with the motor and the first mentioned means for operating the latter, means for closing the door, a member at the compartment movable by the door when the door is closed, means cooperating with the member and the circuit for opening the circuit at the said time when the member has not been moved by the door, and means on the door for rendering the third mentioned means inoperative when the door is open. 10
44. In a sterilizer, a motor with a circuit, a compartment, a door for closing the compartment, means for closing the door, means for sterilizing the compartment operable by the motor at a predetermined time, and means for opening the circuit at the said time when the door is open. 15
45. In a sterilizer, a motor with a circuit, a compartment, a door for the compartment, means for closing the door, means for sterilizing the compartment operable by the motor at a predetermined time, a member at the compartment movable by the door, means cooperating with the member and the circuit for opening the latter at the said time when the member is not moved by the door, and means cooperating with the door and the third mentioned means for operating the latter when the door is open at the said time. 20
46. A compartment, a boiler having communication with the compartment, a cylinder for holding a charge of fluid to charge the boiler for a complete operation, the cylinder communicating with the boiler, a piston in the cylinder for forcing the fluid into the boiler, means for heating the boiler, and means for operating the piston and the said first mentioned means simultaneously. 25
47. In a sterilizer, a compartment, a seat member for disposal in the compartment, a boiler, a cylinder for supplying fluid to the boiler, a piston in the cylinder for forcing the fluid into the boiler, and a communicating means leading from the boiler into the compartment and having a plurality of baffled outlets spaced apart in the compartment. 30
48. In a sterilizer, a compartment, a seat having an enclosed cavity for disposal in the compartment, a boiler, a cylinder for supplying fluid to the boiler, a piston in the cylinder for forcing the fluid into the boiler, a communicating means leading from the boiler to the compartment, and a valve means commanding communication with the cylinder and with the cavity in the seat. 35
49. In a sterilizer, a seat having an enclosed cavity, means to apply a sterilizing fluid to the outer surface of the seat, and means for subsequently cooling the seat by introducing a cooling fluid into the cavity. 40
50. In a sterilizer, a seat having an enclosed cavity, means to sterilize the outer surface of the seat, and means to subsequently cool the seat by introducing a cooling fluid into the cavity and a cooling fluid at the outer surface of the seat. 45
51. In a sterilizer, a compartment, a seat for disposal in the compartment, the seat having an enclosed cavity, a boiler, means for supplying fluid to the boiler, a communicating means leading from the boiler into the compartment, and a valve communicating with the first mentioned means and with the cavity in the seat, the valve in one position opening communication with the cavity in the seat and in another position opening communication with the first mentioned means and with the cavity in the seat. 50
52. In a sterilizer, a compartment, a seat for disposal in the compartment, the seat having an enclosed cavity, a boiler, a cylinder for supplying fluid to the boiler, a piston in the cylinder for forcing fluid into the boiler, a communicating means leading from the boiler into the compartment, valve means communicating with the cylinder and with the cavity in the seat, means to heat the boiler, and means cooperating with the valve means and the third mentioned means for rendering the third mentioned means inoperative when the pressure at the valve means falls below a predetermined point. 55
53. In a sterilizer, a compartment, a seat having an enclosed cavity for disposal in the compartment, a boiler, a cylinder for supplying fluid to the boiler, a piston in the cylinder for forcing the fluid into the boiler, a communicating means leading from the boiler to the compartment, and a valve means commanding communication with the cylinder and with the cavity in the seat, means to heat the boiler, means to operate the piston, and means cooperating with the valve means and the third and fourth mentioned means for rendering the third and fourth mentioned means inoperative when the pressure at the valve means falls below a predetermined point. 60
54. In a sterilizer, a compartment, a seat member for disposal in the compartment, the seat member having an enclosed cavity, an outlet, a valve controlling communication between the compartment and the outlet, and a second valve controlling communication between the cavity in the seat member and the outlet. 65
55. In a sterilizer, a compartment, a seat member hinged for movement into the compartment, the seat member having a cavity, an outlet adjacent the hinge, a valve for controlling communication between the compartment and the outlet. 70

ment and the outlet, and a second valve at the hinge for controlling communication between the cavity and the outlet.

56. In a sterilizer, a compartment, a seat member hinged for movement into the compartment, the seat member having a cavity, an outlet adjacent the hinge, means for introducing a fluid into the compartment, a valve controlling communication between the compartment and the outlet, a pipe for supplying the cavity in the seat with a fluid, and a second valve at the hinge for connecting the pipe with the cavity and the cavity with the outlet.

57. In a sterilizer, a motor having a circuit, a seat, means cooperating with the motor and the seat for moving the latter, means for opening and closing the circuit, cam means cooperating with the first and second mentioned means for operating the latter, and additional means cooperating with the first and second mentioned means for operating the latter.

58. In a sterilizer, a motor having a circuit, a seat, means cooperating with the motor and the seat for moving the latter, means for opening and closing the circuit, cam means cooperating with the first and second mentioned means for operating the latter, additional means cooperating with the first and second mentioned means for operating the latter, and a manually operable means for operating the second mentioned means.

59. In a sterilizer, a compartment, a seat for disposal in the compartment, the seat having an enclosed cavity, a boiler, a valve means connected with the boiler and with the cavity, means to heat the boiler, and means cooperating with the valve means and the second mentioned means for rendering the second mentioned means inoperative when the pressure at the valve means falls below a predetermined point.

60. In a sterilizer, a compartment, a seat for disposal in the compartment, a boiler connected with the compartment, a valve means connected with the boiler, means to heat the boiler, and means cooperating with the valve means and the second mentioned means for rendering the second mentioned means inoperative when the pressure at the valve means falls below a predetermined point.

61. In a sterilizer, a compartment, a boiler connected with the compartment, a communicating means connected with the boiler, means including an electric circuit for heating the compartment, a switch in the circuit which is closed for a predetermined time, a cam means and means connecting the cam means for regulating the action of the switch.

62. In a sterilizer, a compartment, a door for closing the compartment, a boiler connected with the compartment, a circuit for heating the compartment, a switch for the circuit,

means including a motor for moving the door relatively to the compartment, and means cooperating with the second mentioned means and the switch for moving the latter.

63. In a sterilizer, a compartment, a door for closing the compartment, a boiler connected with the compartment, a circuit for heating the compartment, a switch in the circuit means including a motor for moving the door, means for cooling the compartment, and means cooperating with the first mentioned means and the switch and the second means for moving the switch and for cooling the compartment.

64. In a sterilizer, a compartment, a door for closing the compartment, a boiler connected with the compartment, a circuit for heating the compartment, a switch in the circuit, means for cooling the compartment including a valve, means including a motor for moving the door, a member operatively engaging the switch and the valve to permit the switch to move when the member moves in one direction and to move the valve when the member moves in another direction, and a third means cooperating with the second mentioned means and the member for operating the latter.

65. In a sterilizer, a compartment, a door for closing the compartment, a valve at the compartment, a boiler connected with the compartment, a circuit for heating the compartment, a switch in the circuit, means for cooling the compartment including a valve, means including a motor for moving the door, a member operatively engaging the switch and the second mentioned valve to permit the switch to move when the member moves in one direction and to move the valve when the member moves in another direction, and means cooperating with the second mentioned means and the member for operating the latter.

66. In a sterilizer, a motor having a circuit, a compartment, a door for the compartment, means connecting the motor with the door for moving the door relatively to the compartment, a switch in the circuit, and means cooperating with the first mentioned means and the circuit for closing a portion of the circuit to energize the motor after the switch has been closed and opened.

67. In a sterilizer, a motor, a compartment, a door for the compartment, means connecting the motor with the door for moving the latter, a solenoid, a circuit connecting the motor with the solenoid, a second circuit connected with the first mentioned circuit, a switch in the second mentioned circuit, a third circuit connecting the solenoid with the second mentioned circuit, a second switch in the third mentioned circuit, means cooperating with the first mentioned means and the second mentioned switch for moving the latter, and means cooperating with the solenoid

and the first mentioned switch for regulating the action of the latter.

68. In a sterilizer, a motor, a seat, means connecting the motor with the seat for moving the latter, a solenoid, a circuit connecting the motor with the solenoid, a second circuit connected with the first circuit, a switch in the second mentioned circuit, a third circuit connecting the solenoid with the second mentioned circuit, a second switch in the third mentioned circuit, means cooperating with the first mentioned means and the second mentioned switch for moving the latter, means cooperating with the solenoid and the first mentioned switch for regulating the action of the latter, a third switch operable by the first mentioned means, a fourth circuit connecting the third mentioned switch with the second mentioned circuit, a fifth circuit connecting the third circuit with the third mentioned switch, a fourth switch in the fifth mentioned circuit, and means cooperating with the solenoid and the fifth mentioned switch for regulating the latter.

69. In a sterilizer, a motor, a seat, means connecting the motor with the seat for moving the latter, circuit means connected with the motor, a switch for closing the circuit means, a second switch in the circuit means operable by the first mentioned means after the motor has run a predetermined time to close the circuit means irrespective of the position of the first mentioned switch.

70. In a sterilizer, a motor, a seat, means connecting the motor with the seat for moving the latter, circuit means connected with the motor, a switch for closing the circuit means, a second switch in the circuit means operable after the motor has run a predetermined time to close the circuit means irrespective of the position of the first mentioned switch, means operatively connecting the first mentioned means with the second mentioned switch for operating the latter, and a third switch in the circuit means operable by the first mentioned means.

71. In a sterilizer, a motor, a seat, means connecting the motor with the seat for moving the latter, circuit means connected with the motor, a switch for closing the circuit means, a second switch in the circuit means operable by the first mentioned means after the motor has run a predetermined time to close the circuit means irrespective of the position of the first mentioned switch, an auxiliary circuit connected with the circuit means, a third switch in the auxiliary circuit, means cooperating with the first mentioned means and the third mentioned switch for moving the latter, and a fourth switch for the auxiliary circuit.

72. In a sterilizer, a motor, a seat, means connecting the motor with the seat for moving the latter, circuit means connected with the motor, a switch for closing the circuit

means, a second switch in the circuit means operable by the first mentioned means after the motor has run a predetermined time to close the circuit means irrespective of the position of the first mentioned switch, an auxiliary circuit connected with the circuit means, a third switch in the auxiliary circuit, means cooperating with the first mentioned means and the third mentioned switch for moving the latter, a fourth switch for the auxiliary circuit, a solenoid in the circuit means, and means operable by the solenoid for moving the fourth mentioned switch.

Signed at 405 Lexington Avenue, New York city, in the county of New York, and State of New York, this 12th day of June, 1931.

ROBERT E. PETERSON.
